UNITED STATES PATENT OFFICE

2,345,757

EXPLOSION-PROOF SWITCH HOUSING

Ray F. Lester, Syracuse, N. Y., assignor to Crouse-Hinds Company, Syracuse, N. Y., a corporation of New York

Application February 2, 1940, Serial No. 317,022

2 Claims. (CL 200—168)

This invention relates to switch housings designated as the explosion proof type employed to house switches and other electrical apparatus in hazardous locations.

The embodiment of the invention here shown is intended particularly for use in hospital operating rooms where there is likely to be present ether, or other inflammable vapors. The structure herein referred to is intended to be mounted in the wall of the operating room near or adjacent the floor, and involves a particularly durable structure permitting the switch to be operated by the foot to avoid the necessity of the surgeons, and operating room attendants, operating the switch manually by hand. It is desirable in mounting switches in such locations that the exposed surface of the switch be of attractive finish and be properly mounted so that the cover member of the switch is properly fitted against the wall of the room.

The invention has as an object a switch housing of the type referred to embodying a structure by which the body of the housing may be installed in the wall structure and connected in the conduit system during the construction of the building, a cover member in which the switch actuating mechanism is mounted, and an intermediate member carried by the body and in which the switch is mounted, the intermediate member being adjustable toward and from the surface of the wall so that the cover member is properly mounted on the finished wall surface of the room in a neat and attractive manner.

The invention has as a further object a switch housing of the type referred to embodying a structure effecting an efficient flame-tight joint between the cover member and the intermediate member.

A further object of the invention is a switch housing embodying a structure whereby the elements subsequently installed on the body of the fitting and which enclose the switch may be properly sealed as a flame-tight unit at the factory with the leads from the switch, or other apparatus, mounted in the housing extending from said unit for connection within the body member to the conductors in the conduit system, and the unit quickly and conveniently installed in the body, whereby the complete housing forms a tight explosion proof enclosure for the apparatus mounted therein.

The invention consists in the novel features and in the combinations and constructions herein-after set forth and claimed.

In describing this invention, reference is had 55 to the accompanying drawings in which like characters designate corresponding parts in all the views.

Figure 1 is a top plan view of a switch housing embodying my invention.

Figure 2 is a sectional view taken on line 2—2, Figure 1.

Figure 3 is a top plan view of a switch housing generally similar to that shown in Figures 1 and 2 embodying the modified mounting for the switch and a thermostatic actuating mechanism.

Figure 4 is a view taken on line 4—4, Figure 3.

Figure 5 is a top plan view of a modified form of the switch housing shown in Figures 1 and 2.

Figure 6 is a sectional view taken on line 6—6, Figure 5.

The invention consists of a body member in the nature of a conduit outlet box which may be installed in the wall structure and connected in the conduit system. A sleeve is threaded into the outlet box and a cover member secured to the outer end of the sleeve. The sleeve is threaded into the box to provide adjustment of the cover member to properly position the same against the wall surface. The switch is mounted within the sleeve member and is actuated to on and off position by switch operating mechanism mounted in the cover member. The construction is such that the body, sleeve, and cover member, form an explosion proof housing for the switch. If it is desired to have the switch housing effectively sealed from the conduit system, the invention further contemplates a cup shaped member arranged in the sleeve embodying a structure whereby the wires connected to the switch are sealed in the bottom of the cup-shaped member and the cover forming a flame-tight or explosion proof closure for the open end of the cup shaped member.

The body 10 may be of any desired form, it being here shown as of circular formation and provided with a plurality of radially extending hub members 11 provided with an internally threaded passage 12 to receive the ends of the conduits. The body 10 is provided at one side 40 with an internally threaded opening into which an internally threaded sleeve 13 is threaded. The sleeve 13 is formed at its outer edge with a radial flange 14 formed with a plurality of concentric annular shoulders 15 arranged in step formation.

In Figures 1 to 4, a cup shaped member 16 is mounted within the sleeve 13 and is likewise formed with a radial flange 17 formed with an intermediate portion 18 extending in angular relationship to the axis of the cup shaped member. Both the inner and outer sides of the in-

termediate portion 18 is formed with a plurality of concentrically arranged annular shoulders, those on the inner or under side of the flange being complementary to the shoulders 15 formed on the sleeve.

The housing is completed by a cover member 20 having an annular portion 21 overlying the flange 17 and the intermediate portion 18, and extending outwardly to form a marginal flange 22 overlying the adjacent finished surface of the wall 23. That portion of the cover overlying the intermediate portion 18 of flange 17 is formed with a step formation 24 complementary to the step formation on the outer surface of the intermediate portion 18. The arrangement is such that the step formation 24 of the cover member is also complementary to the step formation 15 on sleeve 13. Where it is not necessary to seal off the interior of the switch housing from the conduit system, the cover 20 may be mounted directly on the sleeve 13, as illustrated in Figure 6.

In Figures 1 and 2, the switch 25 is carried by a supporting plate 26 mounted on inwardly extending projections 21 formed on the cup shaped member 16. The switch actuating mechanism is carried by the cover member 20, the cover being formed with a boss 28 extending outwardly and at an angle to the axis of the housing and being formed with an aperture 29, the inner portion of which is threaded to receive a bushing 30. An operating stem 31 is slidably mounted in the bushing 30 and a button 32 is secured to the outer end of the stem 31 and is slidably mounted in the recess 29. The stem 31 and button 32 are urged outwardly by a helical compression spring 33 encircling the stem and the outer end of the bushing 30. In Figures 5 and 6, the cover 20 is provided with a pair of operating buttons 32, and a pair of switches 25 are mounted within the sleeve 13 on inwardly extending bosses 34.

In Figures 3 and 4, the cover 20 is of substantially flat circular formation and is formed with a threaded aperture to receive a bushing 35 in which is rotatably mounted a stem 36. A mercury tube switch 37 is secured to the lower end of the stem 36, and the stem is oscillated in the bushing 35 by a thermostat mechanism indicated at 38 enclosed in a housing 39 mounted upon the cover.

The bottom wall of the cup shaped member 16 is formed with one or more apertures to permit the passage of conductors 40 from the interior of the body 10 to the interior of the cup shaped member 16. These apertures are formed in a transversely extending thickened portion 41 formed with internal flanges 42 at the top and bottom of each passage. After the conductors 40 have been extended through the passages, the passages are filled with a sealing medium 43 and the flanges 42 assist in holding the sealing medium in the passages.

Preferably, the leads 40 are extended through the passages in the bottom of the cup shaped member and the leads sealed in said passages, the switch 25, 37 installed, and the cover 20 secured to the flange 17, as by screws 46, all at the factory. To install the switch, it is only necessary for the workman to screw the sleeve 13 into the body 10 the proper distance to bring the flange 22 of the cover in close proximity to the finished wall surface 23. Thereafter, the ends of the leads 40

extending through the bottom of the member 16 may be connected to the conductors of the conduit system and the unit comprising the cup shaped member with the cover 20 attached thereto inserted in or mounted upon the sleeve 13, as by screws 47.

This procedure avoids the necessity of the workman disrupting the joint between the cup shaped member and the cover and disturbing the factory seal about the leads 40. The sleeve 13 provides a convenient means for adjusting the cover 20 to effect proper mounting of the same relative to the finished wall surface without in any way twisting or otherwise damaging the wiring connected to the switch. The angularly arranged stem 31 with push button 32 forms a convenient and durable mechanism permitting the switch to be operated by pressing the button 32 with the foot.

What I claim is:

1. An explosion proof switch housing comprising a body for installation within the wall structure of a room and being formed with a conduit receiving aperture and with an opening in one side, a flame tight switch enclosure comprising a cup shaped member and a cover detachably secured in flame tight relation to the open end of said member and having a radially extending flange adapted to overlie the marginal portion about an opening in the wall structure, a switch mounted in said enclosure, lead conductors extending from the terminals of the switch through the wall of the enclosure into said body, switch operating mechanism carried by the cover and being operable externally thereof to move the switch into on and off positions, said conductors and the switch operating mechanism being sealed in flame tight relation in said enclosure, means for supporting said enclosure in the opening of the body in flame tight relation thereto, and said means being operable to adjust said enclosure toward and from the body to position the flange of the cover in contact with the wall surface.

2. An explosion proof switch housing comprising a body formed with a conduit receiving aperture and with an opening in one side, a sleeve threaded into said opening and being formed at its outer end with an annular flange, a flame tight switch enclosure comprising a cup shaped member arranged in said sleeve and having a radially extending flange overlapping the flange on said sleeve, the confronting surfaces of the flanges of said cup shaped member and sleeve being formed with a plurality of complementary annular shoulders arranged in step formation, a switch mounted in said enclosure, lead conductors extending through the wall of the enclosure into said body, a cover detachably secured to the open end of said cup shaped member in flame tight relation thereto, switch operating mechanism carried by the cover and being operable externally thereof to move the switch into on and off positions, said conductors and switch operating mechanism being sealed in flame tight relation in said enclosure, said sleeve being of appreciable length and operable to adjust the enclosure toward and from the body, and means operable to detachably clamp the flanges of said sleeve and cup shaped member together.

CERTIFICATE OF CORRECTION.
Patent No. 2,345,757.

April 4, 1944.

RAY F. LESTER.

It is hereby certified that error appears in the printed specification of the above numbered patent requiring correction as follows: Page 1, second column, line 46, for "internally" read --externally--; and that the said Letters Patent should be read with this correction therein that the same may conform to the record of the case in the Patent Office.

Signed and sealed this 30th day of May, A. D. 1944.

Leslie Frazer
